Primary Examiner — Jennifer Rivard*Assistant Examiner* — Alison M Oftstun(74) *Attorney, Agent, or Firm* — Donald J. Ersler(57) **CLAIM**

The ornamental design for a fascia mounting bracket, as shown and described.

DESCRIPTION

FIG. 1 is a top perspective view of a fascia mounting bracket incorporating my new design;

FIG. 2 is a bottom perspective view thereof;

FIG. 3 is top plan view thereof;

FIG. 4 is a bottom plan view thereof;

FIG. 5 is a right side view thereof;

FIG. 6 is a rear elevation view thereof; and,

FIG. 7 is a front elevation view thereof.

The broken lines shown in the drawings illustrate portions of the fascia mounting bracket that form no part of the claimed design.

The broken away symbols in the drawings indicate the appearance of any portion of the article between the break lines forms no part of the claimed design.

1 Claim, 5 Drawing Sheets
